UNITED STATES PATENT OFFICE

RICHARD DAVID METCALFE AND JAMES CROXON METCALFE, OF ROMILEY, ENGLAND
STEAM INJECTOR

Application filed January 28, 1931, Serial No. 511,834, and in France November 5, 1930.

This invention relates to steam injectors of the type utilizing exhaust or low pressure steam. Such injectors usually have a supply of live steam known as supplementary live steam for the purpose of increasing the delivery pressure of the injector. They also have a supply of live steam known as auxiliary live steam for working the injector when exhaust or low pressure steam is not available due to the fact that the engine from which the injector normally derives its exhaust or low pressure steam is either not working or is not receiving any steam.

The injector has an automatic valve therein which ensures that the auxiliary live steam supply is available immediately the supply of steam to the engine (from which the injector derives its exhaust or low pressure steam) is cut off. The injector also has an automatically operated valve for closing the passage through which exhaust or low pressure steam passes into the injector when such steam supply is not available. Such automatic valve is opened by live steam pressure when steam is being supplied to the engine, and is closed by a spring when such steam supply is cut off.

In practice it is found that when the steam supply to the engine is restored after it has been cut off, the automatic valve which opens to uncover the passage by which exhaust or low pressure steam enters the injector is opened before such exhaust or low pressure steam reaches the injector, with the result that any air which may be in the pipe line conveying the exhaust steam enters the injector and causes difficulties in re-starting the injector.

One of the objects of our present invention is to provide means for preventing the passage of air into the injector due to the opening of the automatic valve before exhaust or low pressure steam is available at the injector.

Another object of our present invention is

to provide an improved valve for controlling the supplies of auxiliary and supplementary live steam to the injector.

Our invention comprises the provision in the passage leading between the steam chest or steam supply connection of the engine from which exhaust or low pressure steam is derived for working the injector, of a delay valve adapted to limit the rate at which steam from such steam chest or pipe can pass to the injector for opening the valve which allows live steam to pass into the cylinder of the piston which opens the automatic valve controlling the passage by which exhaust or low pressure steam enters the injector, so that such automatic valve is not opened for an appreciable period after steam has been admitted to the steam chest or steam supply pipe of the engine, whereby we ensure that exhaust or low pressure steam from such engine is available at the valve when the latter is opened, but such delay valve allows free flow of steam in a reverse direction.

Our invention further comprises a control valve for the auxiliary and supplementary live steam supplies which when operated positively opens the auxiliary live steam supply connection but only opens the supplementary live steam supply connection after a predetermined amount of opening movement of the auxiliary live steam supply valve, and allows a regulation of the quantity of supplementary steam admitted to the injector.

Referring to the accompanying sheets of explanatory drawings:—

Figure 1 is a diagrammatic view illustrating an exhaust injector installation with its auxiliary and supplementary live steam control valve and the delay valve before referred to.

Figure 2 is a sectional elevation drawn to a larger scale of the delay valve.

Figure 3 is a sectional elevation in diagrammatic form showing the automatic

valve on the injector for opening the passage through which exhaust or low pressure steam enters the injector.

Figure 4 is a sectional elevation of the auxiliary and supplementary live steam control valve.

Figure 5 is a plan view partly in section of such valve, and

Figure 6 is a sectional elevation on the line 6—6 of Figure 4.

10 The same reference letters in the different views indicate the same or similar parts.

a indicates the passage by which the exhaust or low pressure steam enters the injector; *b* the automatic valve which controls 15 the entry of such steam into the injector, such valve being carried by a lever *c* and closed by a spring *d* and opened by a piston *e*. The latter is acted upon by steam obtained 20 through a passage *f* and past a valve *g* from the passage *h* by which auxiliary live steam is supplied to the injector when exhaust or low pressure steam is not available. The valve *g* is on a spindle above which is a 25 valve *i*, the latter being in a chamber *j* to which live steam from the steam chest or the steam supply pipe of the engine supplying the exhaust or low pressure steam to the passage *a* gains access by way of the pipe *k*. When there is steam in the steam chest or 30 steam supply pipe of the engine, that is to say, when exhaust or low pressure steam is available from the engine for the passage *a*, the valve *i* is closed on its seat and the valve 35 *g* is opened. Steam can then pass from *h* to the cylinder containing the piston *e* which opens the valve *b*.

Supplementary live steam passes to the injector by the passage *m*.

40 In order to prevent the valve *i* being closed too quickly after steam has been supplied to the steam engine chest or supply pipe for the purpose of working the engine, there is provided the delay valve (shown in Figures 1 and 2) in the pipe *k*. Such delay valve is lettered *n* and is an automatic valve closing 45 by the difference of pressure at its two sides. It has an aperture *o* through its seat which when the valve closes, permits steam to pass 50 to the chamber *j* only at a reduced rate, so that there is an appreciable period of time after the admission of steam to the steam engine chest or supply pipe before a pressure is accumulated in the chamber *j* sufficient to 55 cause the closing of the valve *i*, the opening of the valve *g* and the passage of steam to the cylinder containing the piston *e*. This delay action, due to the restriction of the rate of flow of steam in the pipe *k* towards the chamber *j*, ensures that exhaust or low pressure steam shall be available at the valve *b* before such valve is opened. We thereby prevent the passage of air into the injector before exhaust or low pressure steam is available.

60 The valve *p* is an automatic valve which

closes on its seat when there is a pressure in the injector greater than in the passage *a*. When the supply of steam to the engine steam chest is discontinued, any return flow from the chamber *j* through the valve *n* is 70 facilitated by the opening of such valve so that though there is a restriction of the flow towards *j* there is no restriction of flow away from *j*. A cock *q* is provided in the delay valve to cut off the steam supply to *j* if the injector is working permanently from the auxiliary live steam supply.

The control of the auxiliary and live steam supplies is effected by the valve shown in Figures 4, 5 and 6, in which a valve stem *r* is 80 connected positively to the valve *s* which controls the auxiliary live steam supply to the pipe or passage *h*, and to a valve *t* which controls the passage of supplementary live steam to the passage *m*, by a connection which 85 allows a certain amount of free movement of the spindle before the valve *t* is opened. It will be seen that the valve spindle has a collar *u* thereon which works in a chamber formed in the back of the valve, such chamber permitting as before described, relative movement of spindle and valve.

The valve *p* is an automatic valve which 90 closes on its seat when there is a pressure in the injector greater than in the passage *a*. When the supply of steam to the engine steam chest is discontinued, any return flow from the chamber *j* through the valve *n* is facilitated by the opening of such valve so that 95 though there is a restriction of the flow towards *j* there is no restriction of flow away from *j*. A cock *q* is provided in the delay valve to cut off the steam supply to *j* if the injector is working permanently from the auxiliary live steam supply.

The control of the auxiliary and live steam supplies is effected by the valve shown in Figures 4, 5, and 6, in which a valve stem *r* is 100 connected positively to the valve *s* which controls the auxiliary live steam supply to the pipe or passage *h*, and to a valve *t* which controls the passage of supplementary live steam to the passage *m*, by a connection which allows a certain amount of free movement of the spindle before the valve *t* is opened. It 105 will be seen that the valve spindle has a collar *u* thereon which works in a chamber formed in the back of the valve, such chamber permitting as before described, relative movement of spindle and valve.

With this arrangement the valve operating handle *v* can be turned to open the valve *s* and pass auxiliary live steam to the injector without opening the valve *t*, but a further movement of the handle *v* will cause the 110 opening of the valve *t* so that both auxiliary and supplementary live steam will pass to the injector, and the quantity of the supplementary steam can be regulated by the amount of opening of the valve *t*.

It will be understood that the auxiliary supply of live steam which works the injector when exhaust or low pressure steam is not available is throttled down to low pressure by means of the nozzle *w* of restricted bore.

The injector may be worked either by the exhaust steam from the steam engine of the locomotive, or the like, upon which the injector is fitted, or it may be operated by the low pressure steam obtained from the intermediate receiver or low pressure steam chest of a compound engine.

The construction shown in Figure 3 has been indicated in a diagrammatic form for the purpose of including various parts which would otherwise be obscure if such figure had been made a correct sectional view of the injector shown in Figure 1. The details of the injector are omitted.

We wish it to be understood that we do not in the present application claim any novelty for the construction of injector shown in Figure 3, but this figure has been included for the purpose of making clear the result achieved by the present invention.

What we claim is:

1. In an exhaust or low pressure steam injector having an automatic valve opened by steam pressure for allowing of the passage of the exhaust or low pressure steam into the injector, the arrangement of a delay valve for retarding the rate of flow of live steam to the injector control fitting so as to delay the production of full steam pressure in such fitting, such valve allowing the free unretarded return flow of steam from the injector control fitting when the live steam supply is cut off.
2. In an exhaust or low pressure steam injector having an automatic valve opened by steam pressure obtained from the valve which controls the supply of auxiliary live steam to the injector when exhaust or low pressure steam is not available, the arrangement of a delay valve in the steam pipe line between the steam chest or supply pipe of the engine from which the injector derives its exhaust or low pressure steam supply and the valve which supplies steam to open the automatic exhaust steam admission valve, so that the latter valve is not opened for an appreciable period after the supply of steam to the said engine has commenced.
3. In an exhaust or low pressure steam injector, an automatic valve opened by steam pressure for allowing of the passage of the exhaust or low pressure steam into the injector, a delay valve for retarding the rate of flow of live steam to the injector control fitting, so as to delay the production of full steam pressure in said fitting, and for allowing the free unretarded flow of steam from said injector control fitting when said live steam supply is cut off, a valve for controlling

an auxiliary live steam supply and a valve associated with said last mentioned valve by a lost motion connection for controlling a supplementary live steam supply so that said supplementary live steam supply is only available after said auxiliary live steam supply has been established.

In testimony whereof we have signed our names to this specification.
